WILLIAM HAGSTROM, OF LINDSBORG, KANSAS, ASSIGNOR, BY DIRECT AND MESNE ASSIGNMENTS, OF ONE-FOURTH TO JOHN ANDERSON AND ONE-FOURTH TO CLARENCE A. ANDERSON, OF SALINA, KANSAS.

SWITCHING DEVICE FOR PARTY-LINE EXCHANGES.

No. 909,403.

Specification of Letters Patent.

Patented Jan. 12, 1909.

Application filed June 11, 1906. Serial No. 321,103.

To all whom it may concern:

Be it known that I, WILLIAM HAGSTROM, a citizen of the United States of America, and a resident of Lindsborg, county of McPherson, and State of Kansas, have invented certain new and useful Improvements in Switching Devices for Party - Line Exchanges, of which the following is a specification.

10 My invention relates to switching devices for party line exchanges and has for its object improvements in such devices.

In the accompanying drawings, Figure 1 is a front elevation of the device in its normal position; Fig. 2 is a similar elevation with the device moved to the position in which it connects its station telephonically to the party line; Fig. 3 is a similar elevation with the device moved to the position from which 20 it may be released so that it may return to its normal position; Fig. 4 is a side elevation of Fig. 1; Fig. 5 is a detail being partial bottom view of Fig. 1; and Fig. 6 is a detached view of some of the operating parts in the same 25 position as Fig. 1.

In the said drawings A is a magnet having a polarized armature and lever B, on the end of which is a pawl C adapted to engage a ratchet wheel D to move it. A holding pawl 30 E prevents a return of the wheel to normal position until released, which return is accomplished by a spring F.

The parts so far described, do not differ in essence from devices already well known, but 35 I believe that it will add to clearness for me to describe at this point the particular functions which the device is intended to perform, and from which the novel features may be more readily understood. In party 40 line telephone exchanges of the type to which this invention pertains there is a telephone line leading from a central office to a series of local stations. At each local station there is a switching device of some kind, 45 the object of which is to place the station in telephonic connection with the line. These devices are operated simultaneously by impulses sent over the line by an operator at the central office. In what is commonly 50 known as the "lock-out" system these devices are arranged to close electrical connections successively to associated magnets. Adjacent to each of these magnets is some form of contact closing device operated by

the magnet, and also some means for holding the contact closing device closed after being operated and until released by the operator at the central office. These associated magnets have a circuit used by the operator for operating the switching mechanisms, and should she choose to send an impulse over this independent circuit at the time when any particular associated magnet is connected thereto by its switching mechanism, the station at which the operated magnet is located will be connected telephonically to the line but other stations will not be so connected. Ordinarily the switching mechanisms are advanced by impulses flowing in one direction over the line and are released by an impulse in the other direction.

The object of my invention is to produce a mechanism which will perform all of the useful functions of the ordinary switching mechanism and its associated magnet, and yet will 75 at the same time dispose of that magnet and its circuit. I accomplish this result within the switching mechanism itself but it should be remembered that the switching mechanism to perform its function must be associated with other similar switching mechanisms at other stations and all connected to a central office by means of a party line.

Returning now to the description of the mechanism, there is attached to the frame 85 work a bracket G on which are two vertically slideable pieces H and J which normally fall by gravity to the position shown in Figs. 1 and 6. On the wheel D is a pin K arranged to strike and raise the slide J when the mechanism is moved to its extreme forward position. On the spindle of the wheel D is an arm L arranged to strike a pin M on the slide H and to raise that slide at some predetermined time between the first and last movements of the wheel D. In a party line having a series of stations the rise of the slide H occurs at station No. 1 just before it occurs at station No. 2; at station No. 2 just before station No. 3; and so on. This result is accomplished by adjusting the arms L of the different stations so that in normal position they will be different distances from the pin M. The slide H is made so as to be capable of comparatively long movement while the slide 105 J is capable of only a short movement.

On the driving pawl C is a laterally projecting pin C' which has a thin edge normally

adjacent to and just above a similar thin edge projecting laterally from the upper end of the slide J. The pawl C moves to either the left or the right of its normal position 5 (figs. 1 and 6) according to the direction of the impulses sent through the magnet A. When the switching mechanism is operated to advance it the pin C¹ moves away from, and consequently does not strike, the upper 10 end of the slide J. When the slide J is in its normal (lowest) position, a movement of the pawl C in the opposite direction causes the thin edge of the pin C¹ to pass over the upper hooked end of the slide J. But when the pin 15 K has struck the slide J and has moved it upward, a backward movement (toward the right) of the pawl C causes the pin C¹ to engage the hook on the upper end of slide J and turn that slide pivotally on the screw stud 20 upon which it slides vertically. When the pawl C moves backward it slides over a fixed pin shown just below the pin C¹, and in sliding over this pin it rises clear of the ratchet wheel D. On the upper end of the holding 25 pawl E is a pin which normally rests against the back face of the slide J. When the slide J has been raised and a backward movement of the pawl C moves the said slide backward, the slide in turn presses the pin on the pawl E 30 backward and thus raises the holding pawl also from engagement with the wheel D. In this condition the spring F is free to return the wheel to its normal position, and this return withdraws the pin K and arm L from 35 under the slides J and H and permits these slides to fall by gravity to their normal position.

On the armature lever B is a lateral arm terminating in a thin projection B¹ which 40 normally lies adjacent to and slightly above a laterally projecting hook on the upper end of the side H. When the slide H is in its normal position a backward movement of the armature lever causes the projection B¹ to 45 pass idly over the hook on the upper end of the slide H, but after the said slide has been raised a predetermined number of steps by reason of contact between the arm L and the pin M, then a backward movement of the 50 armature lever causes the projection B¹ to strike the hook on the upper end of the slide H and turns that slide pivotally upon the screw stud upon which it normally slides. If the slide H has been moved upward more 55 than the predetermined number of steps, then a backward movement of the armature lever causes the projection B¹ to pass idly under the hook on the upper end of the slide H. The number of predetermined upward 60 steps of the slide H before the hook thereon is in position to be engaged by the projection B¹ is usually one, though it may be any desired number, and does not need to be the same number in all the switching mechanisms 65 connected to the same party line. Ad-

justment of the arm L has hereinbefore been stated as the means for bringing the slides H of different mechanisms successively to position to be engaged by the projection B¹, but that result may be partly accomplished by 70 such adjustment and partly by making the slides H or the projections B¹ so that different numbers of vertical steps will be required.

Pivoted at a convenient place is a bell-crank lever N one arm of which projects horizontally along the bottom of the mechanism and the other arm of which projects vertically back of the slide H. On the side of the vertical arm is a projection which normally rests, by reason of the gravity of the horizontal arm, against the back of the upper end of the slide H. Also on the upper end of the vertical arm of the lever N is a piece of insulation which is adjacent to one of a series of contact springs P. These springs are normally not in electrical connection with each other, but when a backward movement of the armature lever B causes a similar backward movement of the slide H, the movement of the slide H causes a movement of the lever N to close the springs P together as shown in Fig. 2.

Pivoted at another place on the framework of the mechanism is an arm R the free end of which has a hook adjacent to the free end of the horizontal part of the lever N. When the wheel D is in its normal position a pin S therein engages the arm R and keeps its hook clear of the lever N, but as soon as 95 the wheel D has moved forward one step the pin S leaves the arm R. If thereafter the lever N be moved to close the springs P as previously described, the hook on the arm R engages the lever N to hold this connection 100 as shown in Figs. 2 and 3. When the wheel returns to its normal position the pin S strikes the arm R and releases it from the arm N whereupon the springs P break electrical connection with each other by reason 105 of their initial tension.

The springs P are those used for completing telephonic connections. When they are in electrical connection with each other, the station is in telephonic connection with the 115 party line over which the switching mechanism is operated, but when they are not in electrical connection with each other the station is cut off from telephonic connection with the line.

It will be apparent to those familiar with party line exchanges that when the operator sends impulses in an operating direction over the line all of the switching mechanisms connected thereto will be simultaneously advanced step by step, and that no impulse in the reverse direction will be effective to release the mechanisms until after they have been moved to the limit of their forward movements. It will also be seen by the pre- 130

ceding description that the non-releasing effect of reverse impulses during intermediate portions of the forward movement is utilized to enable the switch operating magnet to 5 also operate the locking-in connections.

In addition to the parts so far described the mechanism contains certain other devices not directly connected with invention herein sought to be claimed. Thus, there is a 10 contact spring T which is in electrical connection with the wheel D when at normal position, and a second contact spring V which is in electrical connection with the wheel when at its extreme forward movement. As 15 these are related to the circuits used in the party line connections rather than to the switching mechanism, they need no special description.

Assuming the switching mechanism connected to a party line in the ordinary way 20 and the device to be in its normal position, the first operating impulse sent over the line advances the ratchet wheel D one step. This causes the pin S to leave the arm K so that 25 the catch thereon is ready to catch and hold the bell-crank N whenever raised. After a predetermined number of steps the arm L engages the pin M to raise the slide H. If a 30 reverse impulse (commonly called a release impulse) be sent through the magnet A at the time the hook on the upper end of slide H is opposite the projection B¹, the backward movement of the armature will strike this hook and cause the slide H to turn on its 35 point. This movement of the slide H will be communicated to the bell-crank N to raise its lower end so that it will be caught and held in its raised position by the catch lever R. In this condition the bell-crank N closes 40 the electrical connecting springs P as described. If a reverse impulse be not sent at this particular time the projection B¹ moved backward at any other time will not operate the bell-crank N. After a further predetermined 45 number of operating impulses have been sent, the pin K strikes and raises the slide J, bringing its upper end opposite the pin C¹. Upon a reverse impulse being sent at this time the pin C¹ will strike and move 50 backward the slide J, and this slide will in turn strike and raise the holding pawl E. As the driving pawl is also freed from the ratchet wheel by this backward movement, the wheel is free to be returned to its normal 55 position by the spring F. In returning to normal position the pin K and arm L permit the slides H and J to fall back to normal position. The pin S also strikes the lever R to release the bell-crank N, provided that bell- 60 crank had been caught and held as described.

What I claim is:—

1. The combination with a switching mechanism, a releasing device therefor, and a telephone connecting device, of a magnet 65 arranged to move its armature in either of

two directions according to the direction of the impulses sent therethrough, means by which a movement of the armature in one direction serves to advance the switching mechanism step-by-step, means by which 70 both the connecting device and the releasing device are operated by movements of the armature in the reverse direction, and means controlled by the advance movement of the switching mechanism for bringing the connecting device and the releasing device into operative relationship to the armature at 75 different times.

2. The combination with a connecting mechanism, a selecting mechanism therefor, 80 and means by which said mechanisms are returned to normal position when released, of a magnet, and connections operated thereby and so arranged that impulses sent through said magnet serve to successively 85 operate the selecting mechanism, the connecting mechanism and the release for said mechanisms.

3. The combination with a switching mechanism, and a magnet provided with an 90 armature for advancing it, of a telephone connecting device and releasing devices both arranged to be operated by a reverse movement of the armature and both normally disconnected therefrom, and interposing devices moved by the advance of the switching mechanism so as to bring the connecting device and the releasing devices into operative 95 connection with the armature at different times.

4. The combination with contact devices 100 by which a telephone station is placed in or excluded from telephonic connection with a party line, a selecting mechanism, and devices for releasing the contact devices and 105 the selecting mechanism after being operated, of a magnet, and means by which said magnet serves to successively operate the selecting mechanism, the contact devices, and the releasing devices.

5. The combination with a magnet and armature lever therefor, a switching mechanism operated by the magnet, a normally open telephonic connection, and devices for releasing the switching mechanism after being 110 operated, of a device moved by the switching mechanism and serving to place the telephonic connection temporarily in operative relationship with the armature lever, and a separate device also moved by the switching 115 mechanism and serving to place the releasing devices in operative relationship with the armature lever.

6. The combination with a step by step mechanism, and a magnet for advancing it 120 from its normal position, of a telephone connecting device normally not in operative relationship with said magnet, a releasing device for said mechanism also normally not in 125 operative relationship with said magnet, 130

means controlled by said mechanism for placing the connecting device in operative relationship with the magnet at some predetermined step of the said mechanism, and 5 additional means controlled by said mechanism for placing the releasing device in operative relationship with the magnet at a predetermined later step of said mechanism.

7. The combination with a magnet, and a 10 normally open telephonic connection normally not in operative relationship with said magnet, and of a step by step mechanism operated by said magnet, and a device moved by said mechanism and serving to connect 15 said magnet and said telephonic connection in operative relationship with each other.

8. The combination with a switching 20 mechanism, a magnet provided with an armature for advancing it, a telephone connecting device, and releasing devices for said switching mechanism, of devices moved by the advance of the switching mechanism and so arranged as to bring the connecting device 25 and the releasing devices at different times into mechanically operative relations with the armature.

9. The combination with a magnet, and a

step by step mechanism operated by said magnet when impulses flow therethrough in a given direction, of a telephonic connection 30 and releasing devices arranged to be operated by said magnet when impulses flow therethrough in a reverse direction but normally not in a condition to be so operated, and devices moved by said mechanism and arranged to be interposed successively between said magnet and said telephonic connection and between said magnet and said releasing devices so that they may be operated 35 by said magnet.

10. The combination with a movable lever, and a contact mechanism, of means by which the normal movement of the lever serves to bring the lever and the contact mechanism into temporary operative relationship to each other, and means by which a reverse movement of the lever at such time 40 actuates the contact mechanism.

Signed at Chicago, Ill., this 8th day of June 1906.
